UNITED STATES PATENT OFFICE.

ALPHONSE RYO, OF ROUBAIX, NORD, FRANCE.

DOUBLING-WINDING MACHINE.

SPECIFICATION forming part of Letters Patent No. 389,172, dated September 4, 1883.

Application filed September 29, 1886. Serial No. 214,842. (No model.) Patented in France July 2, 1883, No. 156,386, and April 7, 1884, No. 161,396; in Belgium July 24, 1883, No. 62,117, and May 6, 1884, No. 65,052; in England August 2, 1883, No. 3,808, and April 30, 1884, No. 7,035; in Germany August 9, 1883, No. 27,526, and in Austria-Hungary March 11, 1884, No. 47,393 and No. 10,009.

To all whom it may concern:

Be it known that I, ALPHONSE RYO, of the city of Roubaix, Department of the North, France, have invented new and useful Improvements in Doubling-Winding Machines, (for which I have obtained a patent in France, No. 156,386, dated July 2, 1883; in Belgium, No. 62,117, dated July 24, 1883; in England, No. 3,808, dated August 2, 1883; in Germany, No. 27,526, dated August 9, 1883; in Austria-Hungary, No. 47,393 and No. 10,009, dated March 11, 1884; in France, No. 161,396, dated April 7, 1884; in England, No. 7,035, dated April 30, 1884, and in Belgium, No. 65,152, dated May 6, 1884,) of which the following is a full, clear, and exact description, reference being had to the accompanying drawings thereof, in which—

Figure 1 represents a face view of a portion 20 of a machine for six yarns. Fig. 1^a is a detail, hereinafter referred to; Fig. 2, an end view of the machine; Fig. 3, a section looking toward the stop-motion lever. Fig. 4 shows a diagram of the position of the parts when the machine 25 is working normally; Fig. 5, a similar view showing the position of the parts when the stop-motion comes into operation on the breaking of a yarn. Fig. 6 is a side elevation of the lever *k*. Fig. 7 is a plan thereof. Fig. 8 30 is a view of the frame or bracket *f* detached. Fig. 9 shows one of the pivoted thread-guides and its weight. Fig. 10 is a detail view, to be hereinafter referred to; and Fig. 11 is a view of the stop-bar *y*.

35 The same letters of reference indicate like parts in all the figures.

A represents the frame of the machine, and *a* are the bobbins mounted on the upper part thereof, as shown in Figs. 1, 2, 3. The yarn supplied from bobbins *a* passes through the fixed guides *b*, secured to a cross-piece below the bobbins, around the outer side of a roller, *c*, having a roughened surface, to cause the threads to bind slightly and cause a tension. Some 40 force will be required to turn the roller, and hence the thread causing it to turn will be under tension in proportion. The axis of tension-roller *c* is a spindle, *d*, screwed at one end into a cheek-plate or arm, *e*, carried upon the

right-hand arm of the transverse vertically- 50 swinging frame or bracket *f*, hereinafter described. The spindle *d* passes freely through the opposite cheek-plate or arm, *e'*, and projects sufficiently to enable the attendant to grasp it. (See Fig. 1.) The cheeks or arms *e e'* project 55 upward and outward from the frame or bracket *f*, and are braced together by a tie-rod, *g*, against which the yarns pass tangentially, so that the point at which the yarns leave roller *c*, the point at which they touch rod *g*, and 60 the eye of yarn-guide *h* (to be presently described) shall be in a straight line. The frame or bracket *f* is pivoted at *i* upon the frame below the fixed guides *b*, to swing freely on the breaking of a yarn, as hereinafter described, 65 but so as to always hang in the position shown in Figs. 2, 3, and 4 in the normal operation of the machine.

The spindle *h*², upon which oscillate the counterbalanced yarn-guides *h*, is mounted in 70 the arms *f' f'* of the frame or bracket *f* above and in front of the axis *i*, so that on the breaking of a yarn the axis of the yarn-guides, and consequently the guides themselves, (see Figs. 4 and 5,) swing upward, the said guides contacting with a stop-bar, *y*, (to be hereinafter described,) which throws their eyes toward the attendant, whereby the yarns may be readily pieced up. These yarn-guides are mounted between their ends on the spindle *h*², and their 80 inner ends are provided with the depending weight *h'*, while their outer ends have eyes *h*², one such guide being provided for each yarn or thread.

From the upper curved end of the upward 85 and inward curved arm *f'* of the bracket *f* a weight, *j*, is suspended by a chain, *j''*, said weight being also connected at its bottom end to the stop-motion lever *k*, to be presently described, by a chain, whose length is regulated 90 by a nut, *j'*, on the weight and a screw-eye on the upper end of the chain. To the lower end of the frame *f*, in front of its axis, is jointed the rod *l*, which operates a brake (to be hereinafter described) for the purpose of arresting 95 the spool.

o is a shaft provided with blades, and is journaled in slots in the main frame below

- and parallel with the axis of frame f . The shaft may be adjusted more or less closely to the lower edge of frame of bracket f to properly strike the same, and has a pulley 5 (see Fig. 1) for rotating it. This adjustment of the shaft o may be accomplished in any well-known manner—for instance, by mounting it in sliding bearings o' , operated by set-screws o'' .
- 10 The winding bobbin or spool m is mounted between the arms of a vertically-swinging frame, p , hinged to the lower rail, 9 , of the machine-frame, so as to allow of the bobbin or spool rising as its diameter increases.
- 15 p^2 is a stud on one side of frame p , which is adjustable in a slot, p^3 , in said frame and fixed by a nut. Below the swinging frame p and parallel therewith a bracket, r , is secured to a cross-piece, s , of the frame A .
- 20 k is the brake-operating bell-crank lever pivoted at its angle to the bracket r to swing vertically, the inner end of its long arm being weighted as at k^3 and connected to the chain below the weight j .
- 25 In the normal working of the machine the vertical forward side of the stud p^2 bears against the face k^4 of the short arm of the weighted lever k , which is curved to an arc of a circle described from the pivot of frame p as a center. (See Figs. 3 and 6.) Contact of the two parts p^2 k^4 is insured by regulating the tension of the lower chain of weight j by means of nut j' and the screw-eye. The weighted end of the lever k will keep it in position by causing the curved face k^3 to bear against the stud p^2 . The object of the curved face k^4 of the lever k is to prevent the constantly-increasing size of the bobbin producing any effect upon the frame for the weighted 30 thread-guides. The weighted lever k also carries the guide-rod k' , extending across the under side of the frame p , and beneath which the doubled yarn passes to the winding-bobbin, said rod being so arranged with reference to the pivot of lever k that on the stop-motion coming into action it will be carried inwardly or toward the frame as the frame p is swung upwardly, so as to allow room for the attendant to introduce her hand. This rod 35 k' guides the doubled threads to the guide u^2 , hereinafter described. When the bobbin or spool has attained the desired size, the stud p^2 , which rises with the frame p , will pass beyond the curved face k^4 of the lever k and rest upon the incline k^2 , thereby allowing the weighted end to fall. (See dotted lines, Fig. 5.) To the bracket r is pivoted a bell-crank lever, t , carrying the leather tongue or brake t' , which is to be inserted between the bobbin and its 40 friction-drum n for stopping the motion. The lever t is connected to the lower end of the rod l and operated thereby, and the yarn is led from the rod l through a small guide, u^2 , (see Fig. 1^a.) soldered or otherwise attached to a rod, u' , working in guides u on the outer end of the frame r , and receiving to-and-fro motion from a cam, u^3 , in the groove of which

runs a pin on the carrier, (not shown,) to which the end of the reciprocating rod u' is fixed, as will be readily understood. This 70 guide u^2 is open at its top; but the rod k' , under which the threads pass, holds them down and prevents their disengagement from said guide, except when the rod and frame p are swung, respectively, inwardly and upwardly. 75 The cam u^3 has a gear, u^4 , with which meshes a gear, n^2 , on the shaft of the friction-drum n .

y is an adjustable stop-bar secured to the frame A , behind the bracket f and projecting therethrough above the axes of the thread-guides h . The stop-bar y has slots y' in the inner ends of its arms, and set screws y'' pass therethrough into a part of the main frame. A U-shaped cross-wire, v , fixed by its downwardly-bent ends in holes in a rail, v' , secured 85 to the frame A in front of the bracket or frame f , serves to hold down those guides h which are not in use and which act as a support for those which are in use, the former being below and the latter above it. 90

The operation of the machine is as follows: The yarn or threads pass from the bobbins a down through the guides b , over the front of roller c , under the rod g , through the eyes of the pivotal thread-guides h , thence under the bar or rod k' , through the guide u^2 , to the winding-bobbin. The lower chain of weight, j , is in tension, but has no strain on it, (the weight of the weighted end of lever k being sustained by stud p^2 ,) so as to be in readiness to actuate the 95 stop-motion immediately a yarn breaks. The weight j and rod l are thus in equilibrium during the normal working of the machine, as shown in Fig. 3. When a yarn breaks, the counter-weight h' of its guide h descends into 105 the path of the revolving blades on shaft o , which strike it, forcing it against the lower end of the bracket or frame f , thereby throwing the lower end of the bracket outward and upward and its arms $f' f''$ and roller c inward 110 and causing the leather tongue or brake to be advanced between the bobbin and the friction-drum through the medium of rod l and bell-crank lever t , thus arresting the bobbin. The weight j at same time drops slightly and 115 slackens the lower chain, so that immediately the bobbin-holder is raised on its pivot p by the attendant lifting the projection x the lever k falls, bringing the incline k^2 at the top of its short arm beneath the stud p^2 , and thereby holding the bobbin raised. The lever in falling also puts the lower chain, j , in tension. The brake is also applied whenever the frame p is swung up a sufficient distance to disconnect the stud p^2 from the incline k^2 , as 120 the weighted end of said lever will then drop, and, through the medium of the weight j , connection j' , frame f , rod l , and lever t , throw forward the tongue t' .

The combined effect of raising the axis of 130 the yarn-guides h by the oscillation of frame or bracket f and their arrest at the same level by the adjustable stop-bar y is to throw their eyes well forward within reach of the attendant, so

as to render easy the piecing up of the yarn. The guides strike the stop-bar *y* just in front of their pivotal points *h*², so that their eyes or outer ends cannot be swung too far inward, but 5 are thrown forward within reach of the attendant, as just stated. The oscillation of the bracket or frame *f* also causes the yarn-guides *h* to bear against the fixed bar *y*, while their center is displaced and occupies the position 10 seen in Fig. 5, thus raising their balance-weight *h'* sufficiently to move them out of the path of blades *o*.

To restart the machine, it is simply necessary to pull the tension-roller *c* forward by the projecting end of its spindle, thus releasing the brake-tongue, putting the weighted chain *j* again in tension and raising weighted end of lever *k*, thus throwing its end *k*² from under the stud *p*², by which the bobbin-holder is 20 supported, and allowing the bobbin to again resume contact with its friction drum and re-commence the winding. I have described but one set of the above mechanisms, (though the drawings show the frame A carrying two sets,) 25 as both are exactly alike.

I claim—

1. The combination, with the frame, the pivoted bracket thereon provided with outwardly-inclined arms, a roller journaled in 30 the outer ends thereof, thread-guides pivotally connected between their ends with said bracket between its axis and the said roller, and counter-balances depending from the inner ends of the said guides and extending down behind the 35 rear side of the pivoted bracket, of a revolving-armed shaft below the said counter-balances and into the paths of the arms of which the said counter-balances fall upon the breaking of the threads, a brake or stop, and connections between the pivoted bracket and said 40 brake or stop, substantially as set forth.

2. The combination, with the bracket *f*, pivoted between its ends to swing vertically, outwardly and upwardly inclined arms *e e'* thereon, the roller *c*, journaled in the outer ends of the arms, and the cross-rod *g*, connecting said arms below and in rear of the axis of the roller, of the thread-guides *h*, pivoted between their ends in said bracket in front of 50 and above its axis, the forward ends or eyes of the guides extending adjacent to the cross-rod *g*, the counter-balances *h'*, depending from the inner ends of the said guides alongside the rear face of the bracket, the armed shaft *o*, a 55 brake or stop below said bracket, and connections between the bracket and stop motion, substantially as set forth.

3. The combination, with the frame of the machine, the vertically-swinging bracket *f*, pivoted therein between its ends, the roller *c*, journaled in said bracket, the thread-guides *h*, pivoted between their ends in the bracket between its axis and roller, the counter-balances *h'*, depending from the inner ends of the guides 60 along the rear face of the bracket, of the shaft *o*, having blades or arms for striking said counter-balances and throwing the lower end

of the bracket forward, and the stop *y*, secured to the frame and projecting between the arms of the bracket and into the path of the outer 70 ends of the thread-guides, substantially as set forth.

4. The combination, with the machine-frame, the swinging brackets *f*, and the thread-guides *h* pivoted therein, of the U-shaped cross-pieces, *v*, the downward-projecting arms of which are mounted in the frame below the forward ends of the thread-guides to support those in use and also adapted to hold down the guides not in use, substantially as set forth. 75

5. The combination, with the frame of the machine, the swinging bracket *f*, pivoted between its ends thereon and provided with the roller *c* at the outer ends of its forward arms, and having a rearward-extending arm, *f'*, 80 above its axis, the weight *j*, suspended from the arm *f'*, the thread-guides *h*, pivoted between their ends in said bracket and having counter-balances *h'* depending from their inner ends along the rear face of the bracket and 85 below its axis, and the shaft *o*, having arms or blades to operate said bracket, of the friction bobbin-winding drum against which it bears, a lever having a tongue extending to a point near the drum, and a rod connecting 90 the lower forward end of the bracket *f* with said lever, substantially as set forth.

6. The combination, with the swinging bracket *f* and its thread-guides, of the friction-drum, the vertically-swinging frame above the 95 drum having a stud, *p*³, on one side, a lever connected with the lower forward end of bracket *f* and having a tongue or brake, the bell crank lever *k*, pivoted at its angle below the frame *p* and bearing at the inner face of 100 its upward-extending short arm against the stud *p*² and weighted at the inner end of its horizontal arm, and a connection between the said lever *k* and the upper inner end of the bracket *f*, whereby, when frame *p* is raised to 105 release lever *k*, the weighted end of lever *k* will fall, and the tongue or brake will be applied automatically through the medium of frame *f*, substantially as set forth.

7. The combination, with the swinging bobbin-frame *p*, having a stud, *p*², and the friction drum *n*, of the lever *k*, pivoted at its angle, formed with a curved face, *k*⁴, on the inner side of its short arm, concentric with the axis of the frame *p*, and inclined face *k*² at 110 the upper end of its short arm, the end of the long arm of the lever being weighted, as at *k*³, substantially as set forth.

8. The combination, with the frame of the machine, the swinging frame *p*, the stud *p*² 115 thereon, the friction drum *n*, the bell-crank lever *t*, and the tongue or brake *t'*, of the lever *k*, having a curved face, *k*⁴, resting normally against the stud *p*², inclined upper end, *k*², and weighted long arm, the thread-guides 120 *h*, and their weights *h'*, operated upon the breaking of a thread, the swinging bracket to which said guides are pivoted, the chain connecting the rear upper end of said bracket 130

with the weighted end of lever k , a weight, j , between the ends of the chain and the rod l , connecting the forward lower end of the bracket with the lever t , substantially as set forth.

5 9. The combination, with the frame p , stud p^2 , and friction drum n , of the lever k , having curved face k^2 , inclined end k , weighted long arm k^3 , and laterally-projecting rod k' , to extending transversely across the under side

of the frame p to guide the threads, substantially as set forth.

The foregoing specification of my improvements in doubling-winding machines signed by me this 15th day of September, 1886.

ALPHONSE RYO.
